UNITED STATES PATENT OFFICE

97,506

DESIGN FOR A VENDING MACHINE CABINET

William H. Rowe, Detroit, Mich., assignor to Rowe Manufacturing Co., Inc., New York, N. Y., a corporation of New York

Application September 13, 1935, Serial No. 58,543

Term of patent 7 years

To all whom it may concern:

Be it known that I, William H. Rowe, citizen of the United States, residing at Detroit, county of Wayne, State of Michigan, have invented a new, original, and ornamental Design for a Vending Machine Cabinet, of which the following is a specification, reference being had to the accompanying drawing, forming a part thereof, and which is a perspective view of a vending machine cabinet showing my new design.

I claim:

The ornamental design for a vending machine cabinet as shown.

In testimony whereof I have hereunto set my hand.

WM. H. ROWE.
